UNITED STATES PATENT OFFICE.

JULIUS ENGELLAND, OF ST. LOUIS, MISSOURI.

LOOSE-LEAF BINDER.

1,397,577.

Specification of Letters Patent.

Patented Nov. 22, 1921.

Application filed January 27, 1921. Serial No. 440,390.

To all whom it may concern:

Be it known that I, JULIUS ENGELLAND, a citizen of the United States, residing at St. Louis, Missouri, have invented a certain new and useful Improvement in Loose-Leaf Binders, of which the following is a full, clear, and exact description, such as will enable others skilled in the art to which it appertains to make and use the same, reference being had to the accompanying drawings, forming part of this specification, in which—

Figure 1 is a detail view of my improved loose leaf binder.

Fig. 2 is a detail view of the front or back cover stiffener.

Fig. 3 is a detail view of the plate used in connection with my improved binder.

Fig. 4 is a modified form of binder clip.

This invention relates to a new and useful improvement in loose leaf binders and particularly to a binder clip which is wholly or partially detachable from the covers which contain the leaves. These clips are made of resilient metal, preferably U-shape in form, whereby when one of the legs of the U is threaded through an opening in the leaf or page, the legs of the clip may be pressed together and inserted in an opening or openings in the back or cover portion of the book and then permitted to spread apart whereupon by the formation of the legs of the U-shaped clip, it will interlock with the cover against accidental displacement.

While I have shown forms of my improved clip as being U-shaped, it is obvious that other shapes may be specially adapted for special purposes and could be made without the least change in the nature and principle of my invention.

In the drawings, 1 indicates the back cover of a book, and 2 the front cover thereof, said covers being connected by back member 3 hinged thereto. As shown in Fig. 2, the stiffener for one of the covers, indicated at 4, is slotted as at 5, to provide a space for the toes or extreme ends of the clips. The inner edge of cover 4 is embraced by a U-shaped strip of metal 6 provided with key-hole or T-shaped openings 7 oppositely

disposed to each other in pairs. This strip 6 when slipped over the edge of the cover stiffener 4 will cover the slots 5 and of course, the openings 7 are left exposed, though any finishing covering material may be employed on the cover after the strip 6 is placed in position. 8 indicates a U-shaped clip made of flat spring metal and near the extremities of this clip are notches 9 on one or both sides thereof. 10 indicates a pile of leaves in dotted lines in Fig. 1, each leaf of which pile, as usual, is perforated as at 11. If it is desired to bind these leaves between the covers, the leg of the clip is passed through the aligned perforations of the leaves and then the legs of the clip are pressed together and inserted in the enlarged portion of the key-hole openings and permitted to spring apart whereby they become locked to the cover and hold the leaves in place. I prefer to mount the legs on the back cover, but, of course, these legs could be arranged on the hinged back piece 3, or on the front cover, if desired.

In Fig. 4 the clip 22 is shown as being made of a heavy wire having slots 23 in its sides which are designed to coöperate with a keeper plate having key hole openings 24.

The operation of my improved loose leaf binder is obvious from the foregoing. To remove the clips from the binder, it is only necessary to spring their legs together and lift them out of their openings in the keeper plates. In this way, the entire pile of leaves may be taken out and if it is desired to place new leaves in position, the clips may be removed so as to properly arrange the new leaves in place, after which the clips are threaded through the perforations of the pile of leaves and by pressing their legs together, they can be placed in position in the opening in the keeper plate and by their natural resiliency, expand into engagement with said keeper plate, locking themselves against vertical movement in either direction.

What I claim is:

A loose leaf binder comprising a cover portion having a keeper plate provided with key hole openings, a detachable U-shaped

spring clip, each leg of which is notched on opposite edges near its lower end and which legs are adapted to be moved toward each other for introduction into the larger portion of said keeper plate openings, said legs springing into the smaller portion of said key-hole openings to receive the edges

thereof in said notches, thereby providing separate and detachable locking engagement for each leg.

10

In testimony whereof I hereunto affix my signature this 22nd day of January, 1921.

JULIUS ENGELLAND.
